S. BY *Sigmund Herzog* ATTORNEY

UNITED STATES PATENT OFFICE.

MAXWELL VIDAVER, OF NEW YORK, N. Y.

METHOD OF INSERTING BRISTLES IN RUBBER PADS.

Application filed January 8, 1920. Serial No. 350,176.

To all whom it may concern:

Be it known that I, MAXWELL VIDAVER, a citizen of the United States, and a resident of New York, in the county of New York 5 and State of New York, have invented certain new and useful Improvements in a Method of Inserting Bristles in Rubber Pads, of which the following is a specification.

- 10 The present invention relates to the manufacture of brushes having bristle-supporting rubber pads. These pads are provided with perforations, into each of which either a single or a group of bristles is inserted, 15 the inner ends of the bristles being provided with heads or offsets, which are covered in some suitable manner with a back sheet, whereby the bristles are permanently mounted in the rubber pad. The most difficult 20 operation in manufacturing these brushes, which are usually hair brushes, consists in the mounting of bristles in the rubber pad, and is due to the fact that the number of bristles to be mounted is very high, and that 25 they are disposed in close vicinity of each other.

The main object of the present invention is to provide a method of mounting bristles on rubber pads, which overcomes the difficulties above referred to in that it is entirely independent of the number of bristles to be inserted and also of the distance at which they are to be mounted in relation to each other. 35 Another object of the invention is to simplify and cheapen the operation of inserting the bristles in the rubber pads.

Two of the many possible apparatus for carrying out the method forming the subject matter of the present application for Letters Patent are illustrated in the accompanying drawings, in which:—

Figure 1 is a plan view of a rubber pad, to which the bristles are to be attached; Fig. 45 2 is a central vertical section taken through part of the apparatus for carrying out the method; Fig. 3 is a similar section of a portion of the said apparatus, on a larger scale; Fig. 4 is a central vertical section taken 50 through a combined perforating and guide member, through which the bristles are introduced into the rubber pad; Fig. 5 is a plan view of a rubber pad perforated pre-

paratory to having the bristles inserted therein; Fig. 6 is a view similar to the one 55 shown in Fig. 2 of modified apparatus; Fig. 7 is a section of a portion of the apparatus shown in Fig. 6, on a larger scale; and Fig. 8 is a vertical section taken through a tubular body, through which the bristles are 60 guided into the perforations in the rubber pad shown in Fig. 5 of the drawings.

Generally speaking, the improved method of inserting bristles in rubber pads consists in perforating the pad, stretching the material surrounding the perforations in the pad 65 so as to enlarge the perforations, inserting then one or more bristles within the perforations, and then permitting the material of the pad to contract upon the inserted bristle or bristles, whereby the bristles or bristles are held in place.

Referring now first to Figs. 1 to 4, inclusive, of the drawings, the numeral 10 indicates a block having a recess 11, shaped to 70 receive an imperforated rubber pad 12. The pad is held within the recess of the block by a perforated guide plate 13, the perforations 14 of which register with holes 15 in the block 10, and their arrangement is such that 75 they correspond to the location of the bristle receiving perforations to be made in the rubber pad. The means for perforating the rubber pad comprises a plurality of vertically arranged tubular members 16, the upper ends of which are attached to and arranged in the holes of a frame 17, while 80 their lower ends are provided with piercing points 18. The frame 17, with the tubular members 16 thereon, is reciprocable in relation to the block 10, it being guided in its 85 movement in any suitable manner, for instance by frame sections 19 of the apparatus. Suitable means must, of course, be provided for bringing the block and the elements thereon in proper relation to the said 90 tubular members.

The manner in which the apparatus is used in inserting bristles in rubber pads in accordance with the method herein described is as follows:—The rubber pad is placed into the recess of the block 10, and the guide plate 13 superimposed upon the said pad. The elements are then put upon a support 10' and brought into operative relation to the frame 17. This frame is then 100 105

lowered, whereby the tubular members 16 thereon are caused to pass through the perforations 14 in the guide plate 13 and perforate the rubber pad. These perforations 5 are enlarged, as the said tubular members complete their downward movement. One or a group of bristles is fed either before or after the perforating operation into each tubular member 16, the tubular members 10 protecting the bristles from contact with the edges of the perforations in the rubber pad and thereby permitting the bristles to be inserted with practically no resistance. The bristles may drop onto the support 10' 15 by gravity, or they may be forced into contact with the said support by any suitable means, not shown. After the tubular members have completed their downward stroke and the bristles have been brought in their 20 lowermost positions, the said tubular members are started on their upward stroke, the elasticity of the rubber causing the apertures therein to contract and closely engage the respective bristles as soon as the tubular members 16 have been disengaged therefrom.

The block and the guide plate 13 are then disengaged from the rubber pad and the bristles thereon, and the bristles cemented 30 or otherwise attached to the said pad, to be placed finally upon a wooden or other brush-back.

As appears from the foregoing, the perforating and stretching operations are performed by the same mechanism, that is to say by the tubular members 16, their piercing points 18 first perforating the pad and their body portions then enlarging the said 35 perforations.

40 It is obvious that the rubber pads may be perforated on a separate machine and the perforations then enlarged on the bristle-inserting device. A device of this type is shown in Figs. 6 to 8, inclusive, differing 45 from the one above described in that the tubular members 16' lack the piercing points. In this instance the rubber pad 12' is provided with perforations 12'' before it is put in the recess of the block 10. The 50 diameters of the perforations 12'' are of course somewhat smaller than the diameters of the bristles. As the tubular members are forced through the perforations 12'', the yielding nature of the rubber permits the 55 perforations to be temporarily enlarged for the purpose above set forth. Otherwise the method is carried out in the manner described in connection with the device shown in Figs. 2 to 4, inclusive.

60 What I claim is:—

1. The method of mounting bristles on rubber pads, which consists in perforating the pad, temporarily enlarging the perforations, inserting one or more bristles within 65 each perforation out of contact with the

walls thereof, and then permitting the material of the pad to contract upon the inserted bristles.

2. The method of mounting bristles on rubber pads, which consists in perforating 70 the pad, employing an enlarging means to temporarily enlarge the perforations, inserting one or more bristles in each perforation, the enlarging means preventing contact between the bristles and the pad, and then withdrawing the enlarging means from the perforations and thereby permitting the material of the pad to contract upon the inserted bristles.

3. That improvement in the art of inserting bristles in an apertured elastic pad 80 which consists in supporting the pad on one side with a plate provided with an opening opposite the aperture in the pad; inserting into the aperture in the pad from its other side a bristle guiding tube, larger than said aperture, whereby said aperture is expanded, and one or more bristles within said tube, and then withdrawing the tube leaving the bristle inserted in the aperture in the 85 pad, and permitting the material of the pad to contract upon said inserted bristles.

4. That improvement in the art of inserting bristles in a rubber pad which consists in confining the pad between two plates, one 90 provided with a perforation and the other with an opening opposite said perforation, inserting through said perforation in the one plate, and the interposed pad, into the opening in the other plate, a bristle-guiding tube, and one or more bristles protected by the tube from contact with the rubber pad, and then withdrawing the tube leaving the 95 bristle inserted in the pad.

5. The improvement in the art of inserting bristles in a rubber pad which consists in providing the rubber pad with a perforation, confining the pad between two plates, one provided with a perforation registering 100 with the perforation in the pad, and the other with an opening opposite said registering perforations in the one plate and the rubber pad, and inserting through said perforations in the one plate and the pad into the opening in the other plate, a bristle-guiding tube and one or more bristles protected by the tube from contact with the 105 walls of the perforation in the rubber pad, and then withdrawing the tube leaving the 110 bristle inserted in the perforation in the rubber pad.

6. That improvement in the art of inserting bristles in a perforated soft-rubber pad 115 which consists in stretching the material surrounding a perforation in the pad to enlarge said perforation, inserting one or more bristles within said perforation, and then permitting the material of the pad to contract upon the inserted bristle or bristles.

7. That improvement in the art of insert-

ing bristles in a perforated rubber pad, which consists in forcing through said perforation a bristle-guiding tube larger than the perforation thereby stretching the material of the pad surrounding the perforation, inserting one or more bristles through said tube so inserted through said aperture

in the pad, and then withdrawing said tube permitting the material of the pad to contract upon the inserted bristle or bristles. ¹⁰

Signed at New York, in the county of New York and State of New York, this 2nd day of January, 1920.

MAXWELL VIDAVER.
